UNITED STATES PATENT OFFICE.

JOHN J. LYTH, OF VALLEYFIELD, QUEBEC, CANADA.

BLEACHERY REEL.

Application filed November 17, 1924. Serial No. 750,435.

This invention relates to improvements in reels for use in bleacheries, finishing rooms and the like and particularly for handling cloth impregnated with corrosive or other liquids, and the main object of the invention is to provide a reel with renewable blocks or bars, which reel may be adjusted to any desired width and equipped with blocks or bars having any desired shape of groove.

A further object is to provide a split reel so constructed that it may be readily applied to or removed from existing shafting.

A still further object is to provide a split reel with removable blocks or bars which may be taken apart for application to or removal from a shaft without disturbing the adjustment of the blocks or bars.

Still another object is to provide a reel having metal spiders.

Various other objects, together with the advantages of the foregoing and other objects may be ascertained from the following description.

25 Briefly described, the reel forming the subject of this invention comprises a pair of similar metal spiders each divided into two or more parts releasably connected together so as to permit attachment to or detachment from an existing shaft without removing the same from its bearings. Each spider comprises a series of spokes terminating in sockets to receive and hold blocks or bars extending between the spiders.

35 These spokes are connected together in pairs adjacent their outer extremities and clamping bolts are passed through the spoke connections midway between the spokes and therefore midway between the blocks or bars

40 carried by the spokes, whereby the clamping effect of each bolt will be equalized between the blocks or bars secured by it and slight inequalities in the length of the blocks or bars compensated for.

45 In the accompanying drawings which illustrate one embodiment of the invention, but to the precise details of which the invention is not confined:—

Fig. 1 is a side elevation of the reel.

50 Fig. 2 is a sectional view on the line 2—2, Figure 1.

Figs. 3 and 4 are sectional views similar to Figure 2 illustrating the adaptability of the spiders to blocks or bars of different shapes.

55 Referring more particularly to the drawings, 11 designates a pair of similar spiders

each composed of a plurality of parts, for example, of two parts 12 and 13 as illustrated, joining at a diameter of the spider and provided with flanges 14 for the passage of bolts 15 to secure the two parts of each spider together and to clamp the same around a shaft. Each spider comprises an even number of spokes 16 radially arranged and connected together in pairs adjacent their outer ends by rim members 17. The spokes of adjoining pairs are not connected, there being open spaces 18 between the spoke pairs corresponding to the position of the rim members connecting the spokes of each pair. The outer end of each spoke is provided with a laterally opening socket 19 to receive the end of a block or bar 20, the opposite end of which is supported in a corresponding socket of the other spider. Each of these sockets comprises a bottom wall 21 inclined with respect to the plane of the spider, an outer wall 22 also inclined to the plane of the spider but in the opposite direction to the wall 21, and a pair of side walls 23 adapted to embrace the end of a block 20. The bottom walls 21 support weight transmitted through the blocks, and their inclination is such that the blocks 20 tend automatically to centre themselves between the two spiders, while the inclination of the outer walls 22 is such that they hold the blocks against removal radially outward. The walls 23 hold the blocks against movement out of their radial disposition and in the circumferential direction of the spiders. Clamping bolts 24 pass through the rim members 17 midway between the spokes connected by such members, with the result that when the bolts are tightened the load imposed thereby is distributed equally between the blocks carried by the pair of spokes. The lack of connection between the spoke pairs at their outer ends enables this effect to be obtained and also makes it possible to take advantage of the elasticity or flexibility of the metal of the spokes to compensate for any slight inequality in the length of the blocks.

55 The ends and inner edges 25 and 26 respectively of the blocks are shaped to conform to the inclination of the walls 22 and 21 respectively, regardless of the length of the blocks between spiders or to the shape of the groove 27 (if any), in the blocks. Figure 2 shows a short block with a narrow V-groove while Figure 3 shows a longer

block with a wide V-groove, and Figure 4 a block with a flat-bottom groove. It will be obvious that in each case the end and inner edges of the blocks are identically shaped where they engage the spiders, and also that the spiders themselves are identical. In short, the only alteration necessary to accommodate the reel to blocks of any desired shape or length is the employment of clamping bolts of suitable length.

10 A reel constructed according to this invention may obviously be separated diametrically for attachment to or removal from a shaft without any disturbance of the 15 clamping bolts and blocks. When it is desired to renew the blocks in a reel, either to replace those worn or broken or to insert blocks of an entirely different shape, it is not necessary to remove the reel from its 20 supporting shaft but merely to loosen the bolts 15 so that the spiders may be moved apart on the shaft for the release of the blocks and to permit the insertion and clamping in place of other blocks. A considerable economy will result from the use of 25 such reels, as reels which are not in use may be readily moved to another part of the mill for use or may be altered as to width and shape of groove merely by the insertion of 30 new blocks without the necessity of purchasing a complete new reel. Should any part 35 of the spiders become broken a maximum of only one-quarter of the reel spider need be replaced, owing to the use of separate and divided spiders at the two ends of the reel; and the amount of replacement may be materially reduced by increasing the number of parts into which each spider is 40 divided.

40 While the invention has been referred to and described only as a bleachery reel, it will be understood that the same principles of construction may be applied to other types of reels as well as to the construction 45 of winding drums, inserted toothed gears and other devices. It will also be understood that alterations may be made in various details of the construction, such as the shape of the socket members, without in any 50 way departing from the spirit of the invention, and therefore all such modifications as fall within the scope of the appended claims are included in and form a part of the invention.

55 Having thus described my invention, what I claim is:—

1. A device of the class described comprising a pair of similar spiders each having an even number of arms, rim members connecting the arm in pairs adjacent their free extremities, members connected between corresponding arms of the two spiders, and bolts passing through the rim members intermediate the arm and clamping said members between the spiders.

2. A device of the class described comprising a pair of similar separable spiders each divided radially into a plurality of parts, means to clamp the parts together about a shaft, removable tooth members extending between the spiders, and bolts passing through the spiders and releasably clamping such tooth members in place.

3. A device of the class described comprising a pair of similar spiders each divided radially into a plurality of parts, means to clamp the parts about a shaft, rim members connecting the spider arms in pairs adjacent their peripheries, members disposed between corresponding arms of the two spiders, and bolts passing through the rim members intermediate the spider arms, and clamping said members between the spiders.

4. A device of the class described comprising a pair of similar spiders, sockets at the extremities of the spider arms, members extending between the spiders and supported at their ends in said sockets, each socket including a pair of side walls to embrace the sides of the contained member, and an end wall shaped to hold the contained member against movement radially away from the spider, rim members connecting the spider arms in pairs adjacent the sockets thereof, and bolts passing through the rim members of both spiders intermediate the arms, each of said bolts serving to clamp two of said members between the spiders.

5. A device of the class described comprising a pair of spiders each radially divided into a plurality of parts each having an even number of arms, means to clamp said parts together about a shaft, rim members connecting the spider arms in pairs adjacent their extremities, the arm pairs being entirely separate at their extremities, sockets at the extremities of the arms, bar, block or tooth members extending between the spiders and entering at their ends into said sockets, bolts passing through the rim members of both spiders midway between the arms connected thereto and clamping the bar, block or tooth members between the spiders.

6. In a device of the class described a body having radiating arms at opposite ends thereof, rim members connecting the arms at each end in pairs adjacent their extremities, members inserted between corresponding arms of the two ends of the structure, and clamping bolts passing from end to end of the structure through the rim members intermediate the connected arms, whereby each bolt serves to clamp two of said members and to flex the arms of the structure as necessary to distribute the clamping load equally between the two members clamped.

In witness whereof, I have hereunto set my hand.

JOHN J. LYTH.
